HENRY S. YOUNG, OF WILKINSBURG, AND ROBERT M. GILSON, OF PITTSBURGH, PENNSYLVANIA, ASSIGNORS TO THE UNION SWITCH & SIGNAL COMPANY, OF SWISSVALE, PENNSYLVANIA, A CORPORATION OF PENNSYLVANIA.

APPARATUS FOR THE CONTROL OF HIGHWAY-CROSSING SIGNALS.

Application filed October 7, 1926. Serial No. 140,010.

Our invention relates to apparatus for the control of highway crossing signals, and particularly to apparatus suitable for use in territory provided with train controlling means 5 of what is known as the "coded" type, that is, the type wherein current is periodically supplied to the track rails for the control of train-carried governing mechanism.

We will describe two forms of apparatus 10 embodying our invention, and will then point out the novel features thereof in claims.

In the accompanying drawing, Fig. 1 is a diagrammatic view showing one form of apparatus embodying our invention. Fig. 2 is a 15 diagrammatic view showing a modification of a portion of the apparatus shown in Fig. 1 and also embodying our invention.

Similar reference characters refer to similar parts in each of the views.

20 Referring first to Fig. 1, the reference characters 1 and 1^a designate the track rails of a railway over which traffic normally moves in the direction indicated by the arrow, but over which traffic may at times move in the opposite direction. These rails are divided by insulated joints 2 to form two track sections A—B and B—C, and a highway Q intersects the railway track at substantially the junction point B of these sections. A highway 25 crossing signal S is located at the intersection of the railway and the highway, and this signal in the form here shown is of the electric bell type.

Section A—B is provided with a track circuit comprising a transformer H the secondary of which is connected across the rails adjacent the point B, and a track relay L^A connected across the rails adjacent the point A. The primary of transformer H is supplied 30 with alternating signaling current from the secondary of a transformer T, the primary of which is constantly connected with a source of current not shown in the drawing. Interposed between transformers T and H is a 35 normally closed contact 15 of a coding device R^B having a controlling circuit which passes from terminal 3 of a suitable source of current through back contact 5 of track relay L^A, back contact 14 of coding device 40 R^B, the winding of coding device R^B, and a front contact 10 of a relay E, to terminal 4 of the same source of current. Assuming that relay E is energized, coding device R^B will be de-energized when track section A—B is un-

occupied, so that signaling current will then 55 be supplied continuously to the rails of this section. When a train enters section A—B, however, the circuit for the coding device R^B will be closed at contact 5, whereupon this coding device will operate to periodically interrupt the supply of signaling current to the rails of section A—B. This periodically interrupted signaling current constitutes what I will term "train control" current.

Section B—C is provided with a track circuit comprising a transformer K the secondary of which is connected with the rails adjacent the point B, and a track relay L^C having two windings 22 and 23. Winding 22 is connected across the rails adjacent point C, and winding 23 is constantly supplied with alternating signaling current from terminals 3 and 4 of a suitable source of such current. A resistance 24 is interposed between winding 22 and one of the track rails 1^a. Relay L^C 75 controls a coding device R^C, the circuit including back contact 19 of relay L^C and back contact 16 of the coding device, so that this coding device is at rest when section B—C is unoccupied and is in operation when the section is occupied. When the coding device R^C is at rest resistance 24 is shunted by back contact 18 of the coding device, whereas when the coding device is in operation this shunt is periodically opened and at the same time 80 alternating current is periodically supplied to the primary of a transformer U from the secondary of a transformer M, through front contact 17 of the coding device R^C. The secondary of transformer U is connected across 90 the rails of section B—C adjacent the point C, and the primary of transformer M is connected with the same source as that which supplies current to the primary of transformer T. The purpose of the resistance 24 is to prevent 95 over-energization of winding 22 of relay L^C by the periodically interrupted current which is supplied to transformer U when relay L^C is de-energized.

The reference character D designates a 100 quick-acting relay which receives energy from the rails of section A—B at an intermediate point in the section, a transformer N preferably being interposed between this relay and the track rails. The reference character E 105 designates a relay having two windings 20 and 21. Winding 20 receives energy from the rails of section B—C at an intermediate point

in this section through the medium of a transformer P , and winding 21 is constantly connected with the alternating current terminals 3 and 4. Relay D is connected with the rails at substantially the point at which it is desired that the crossing bell S should start to operate when a train is moving in the direction indicated by the arrow, and relay E is connected with the rails of section $B-C$ substantially at the point at which it is desired that the bell should start to operate when a train is moving in the opposite direction.

Relays D and E control a slow-releasing relay F , and the relays D , E and F control an interlocking relay G which in turn controls the bell S . The relay G comprises two magnets G^1 and G^2 .

The circuit for the slow-releasing relay F is from terminal 3, through front contact 6 of relay D , front contact 8 of relay E , and the winding of relay F to terminal 4. Magnet G^1 is provided with a first circuit which passes from terminal 3 through front contact 11 of relay F and the winding of magnet G^1 to terminal 4. This magnet is provided with a second circuit which passes from terminal 3, through front contact 6 of relay D , back contact 8 of relay E and the winding of magnet G^1 to terminal 4. Magnet G^1 is provided with a third circuit which passes from terminal 3, through front contact 12 controlled by magnet G^1 , front contact 7 of relay D , and the winding of relay G^1 to terminal 4. Magnet G^2 has only one circuit, and this circuit is controlled by front contact 9 of relay E . The crossing bell S is controlled in the usual manner by contacts 12 and 13 of interlocking relay G .

The operation of the apparatus shown in Fig. 1, is as follows: When the two sections are unoccupied all relays are energized, so that the parts are in the conditions shown in the drawing. When a train moving in the direction indicated by the arrow enters section $A-B$, it de-energizes track relay L^A , thereby causing the coding device R^B to operate whereupon alternating current is periodically supplied to the rails of this section. Relay D will release during the intervals between the impulses of this current, but relay F will remain closed because of its slow-acting characteristic, and, consequently, magnet G^1 of the interlocking relay will remain energized because of the first circuit traced hereinbefore for this magnet. When the train approaches the point at which transformer N is connected with the track rails, relay D will remain open, whereupon relay F will release. All of the circuits for magnet G^1 are then open so that this magnet will release and will start the bell S in operation. When the forward end of the train enters section $B-C$, it will de-energize track relay L^C , and this in turn will start the operation

of the coding device R^C , so that periodically interrupted alternating current will be supplied to the rails at point C by transformer U . The connection of transformer U with the track rails is the reverse of the connection of transformer K with the track rails, so that relay E is not energized to close its front contacts by the current supplied to the rails from transformer U . Relay E accordingly becomes de-energized when the train enters section $B-C$. When the rear end of the train leaves section $A-B$, relay D becomes energized and remains continuously energized because the operation of the coding device R^B is prevented due to the fact that the circuit for this coding device is open at front contact 10 of relay E . The second circuit for magnet G^1 is now closed at front contact 6 of relay D and backs contact 8 of relay E , so that contact 12 opens and stops the operation of the bell S . Magnet G^2 is, of course, de-energized because contact 9 is open, but as is well understood, contact 13 will not close because contact 12 was closed at the time that magnet G^2 became de-energized. After the train passes the point of connection of transformer P with the track rails, relay E will again become energized so that magnet G^2 will become energized, and the closing of front contact 8 of relay E will again energize relay F , so that the parts of the apparatus associated with the crossing bell S are restored to their normal conditions. When the train leaves section $B-C$, track relay L^C will become energized and so will stop the operation of the coding device R^C .

We will now assume that a train moving in the direction opposite to that indicated by the arrow enters section $B-C$. As this train approaches the point of connection of transformer P with the track rails, it will de-energize relay E and this in turn will de-energize magnet G^2 and so will start the bell S in operation. The opening of front contact 8 of relay E de-energizes relay F so that this relay is rendered ineffective to control the interlocking relay G during a train movement in the direction now under consideration. Magnet G^1 remains energized due to its third circuit including its own front contact 12 and contact 7 of relay D . When the forward end of the train enters section $A-B$, it de-energizes relay D , which in turn de-energizes magnet G^1 , so that when the rear end of the train leaves section $B-C$ the bell S stops ringing. When the train leaves section $A-B$, relays D and F will again become energized so that the parts of the apparatus will be restored to their normal conditions.

The circuits for magnet G^1 of the interlocking relay G are such as to insure proper operation of this relay for all train movements including a light engine moving at high speed in the direction opposite to that indicated by

the arrow. Furthermore, it will be noted that relay F is de-energized before such a train reaches point B, so that the slow-releasing characteristic of this relay will not 5 interfere with the proper operation of the interlocking relay G.

Referring now to Fig. 2, the apparatus here shown is suitable for use on an electrified railway wherein the signaling current 10 is of one frequency, such as 60 cycles, and the train controlling current is of another frequency, such as 100 cycles. The signaling current is supplied to section B-C by a transformer K⁶⁰, and the second winding 23 15 of the track relay L^X is normally supplied with 60 cycle current from a transformer V⁶⁰ through back contact 25 of the coding device R^c. The train controlling current is supplied to the rails at the point C by a transformer 20 W, the secondary of which is interposed between winding 22 of relay L^X and the track rail 1^a. When the coding device R^c is at rest, the primary of transformer W is placed on short circuit by contact 17, so that this transformer 25 offers substantially no impedance to the flow of 60 cycle current from transformer K⁶⁰ to relay winding 22. When the coding device R^c is in operation, however, 100 cycle current is periodically supplied to the primary of transformer W from a transformer V¹⁰⁰ through the front point of contact 17, and while this current is being supplied to transformer W, the supply of 60 cycle current to the relay winding 23 is discontinued at 30 contact 25. It follows that when a train leaves section B-C, relay winding 22 will be constantly supplied with 60 cycle current and intermittently supplied with 100 cycle current, but that while the 100 cycle current is being supplied the supply of 60 cycle current will be discontinued in winding 23, so that this relay will become energized even if 35 it is a relay of the centrifugal type.

Although we have herein shown and described only two forms of apparatus embodying our invention, it is understood that various changes and modifications may be made therein within the scope of the appended claims without departing from the spirit 40 and scope of our invention.

Having thus described our invention, what we claim is:

1. In combination, a railway track divided into two successive sections A-B and B-C, 45 a highway intersecting said track at substantially the junction point of said sections, means for supplying periodically interrupted alternating train controlling current to the rails of section A-B adjacent point B and to the rails of section B-C adjacent point C, a source of alternating signaling current connected with the rails of section B-C adjacent point B and the relative polarity of which is the reverse of that of said train controlling current supplied at point C, a quick 50

acting relay D receiving energy from the rails at an intermediate point in section A-B, a relay E having a winding receiving energy from the rails at an intermediate point in section B-C and responsive to the relative 70 polarity of said signaling current but not to that of said train controlling current, a slow acting relay F having a circuit including front contacts of relays D and E in series, an interlocking relay having two magnets G¹ and G², a first circuit for magnet G¹ controlled by a front contact of relay F, a second circuit for magnet G¹ including a front contact of relay D and a back contact 75 of relay E, a third circuit for magnet G¹ including a front contact of relay D and a contact closed when the armature for magnet G¹ is closed, a circuit for magnet G² controlled by a front contact of relay E, and a highway crossing signal controlled by said interlocking relay. 80

2. In combination, a railway track divided into two successive sections A-B and B-C, a highway intersecting said track at substantially the junction point of said sections, means for supplying periodically interrupted alternating train controlling current to the rails of section A-B adjacent point B, and to the rails of section B-C adjacent point C, a source of alternating signaling current connected with the rails of section B-C adjacent point B and the relative polarity of which is the reverse of that of said train controlling current supplied at point C, a quick 90 acting relay D receiving energy from the rails at an intermediate point in section A-B, a relay E having a winding receiving energy from the rails at an intermediate point in section B-C and responsive to the relative polarity of said signaling current but not to that of said train controlling current, a slow acting relay controlled by said relays D and E, and a highway crossing signal controlled by said relays D and E by said slow acting relay. 95

3. In combination, a railway track divided into two successive sections A-B and B-C, a highway intersecting said track at substantially the junction point of said sections, means for supplying periodically interrupted alternating train controlling current to the rails of section A-B adjacent point B, and to the rails of section B-C adjacent point C, a source of alternating signaling current connected with the rails of section B-C adjacent point B and the relative polarity of which is the reverse of that of said train controlling current supplied at point C, a quick acting relay D receiving energy from the rails at an intermediate point in section A-B, a relay E having a winding receiving energy from the rails at an intermediate point in section B-C and responsive to the relative polarity of said signaling current but not to that of said train controlling 100

current, and a highway crossing signal controlled by said relays D and E.

4. In combination, a railway track divided into two successive sections A—B and B—C, 5 a highway intersecting said track at substantially the junction point of said sections, means for supplying periodically interrupted alternating train controlling current to the rails of section A—B adjacent point B, a 10 source of signaling current connected with the rails of section B—C adjacent point B, two relays D and E receiving energy from the rails of sections A—B and B—C respectively, a slow acting relay F having a circuit 15 including front contacts of relays D and E in series, an interlocking relay having two magnets G¹ and G², a first circuit for magnet G¹ controlled by a front contact of relay F, a second circuit for magnet G¹ including 20 a front contact of relay D and a back contact of relay E, a third circuit for magnet G¹ including a front contact of relay D and a contact closed when the armature for magnet G¹ is closed, a circuit for magnet G² controlled 25 by a front contact of relay E and a highway crossing signal controlled by said interlocking relay.

5. In combination, a railway track divided into two successive sections A—B and B—C, 30 a highway intersecting said track at substantially the junction point of said sections, means for supplying periodically interrupted alternating train controlling current to the rails of section A—B adjacent point B, a 35 source of signaling current connected with the rails of section B—C adjacent point B, two relays D and E receiving energy from the rails of sections A—B and B—C respec-

tively, a slow acting relay controlled by said relays D and E, and a highway crossing signal controlled by said relays D and E and by said slow acting relay. 40

6. In combination, a railway track divided into two successive sections A—B and B—C, 45 a highway intersecting said track at substantially the junction point of said sections, means for supplying periodically interrupted alternating train controlling current to the rails of section A—B adjacent point B, a source of signaling current connected with the rails of section B—C adjacent point B, two relays D and E receiving energy from the rails of sections A—B and B—C respectively, and a highway crossing signal controlled by said relays D and E. 50

7. In combination, a section of railway track, a source of signaling current connected with the rails at one end of said section, a track relay connected with the rails at the other end of said section, means including a coding device for at times applying periodically interrupted alternating train control current to the rails at the relay end of said section, a resistance interposed between said relay and one of the rails of said section, and means controlled by said coding device for closing a shunt around said resistance when train control current is not being supplied to the rails and for opening said shunt when train control current is being supplied to the 65 rails. 70

In testimony whereof we affix our signatures.

HENRY S. YOUNG.
ROBERT M. GILSON.
